UNITED STATES PATENT OFFICE.

HARRY J. HUFFORD, OF SCRANTON, PENNSYLVANIA.

THREAD CLEANER.

Application filed October 18, 1928. Serial No. 313,342.

The invention relates to improvements in a thread cleaner of the general type in which two longitudinally tapered thread cleaning blades are relatively adjustable to vary the distance between them according to the size of thread to be cleaned, and it is the principal object of the invention to provide a new and improved construction for tightly holding the blades in relatively adjusted position, in such manner that they cannot by any possibility be moved by an unauthorized person to widen the space between them. Very often unscrupulous attendants of spooling and analogous machines provided with the cleaners, so adjust the blades as to widen space them, thus producing poor work but permitting greater production, and hence, meaning more compensation for the attendant who receives her pay according to the amount of thread spooled. By the use of my invention, such unauthorized adjustments of the cleaner to better the pay of the attendant at the sacrifice of the character of thread, is positively prevented.

Very often, a key-operated set screw is employed to lock the scraping blades in relatively adjusted position and heretofore such screw has been so accessible as to make it possible to loosen it by an instrument other than the proper key. Hence, it has been possible to effect unauthorized adjustment of the cleaner. It is another aim of my invention however to provide novel means whereby the screw is guarded against such tampering.

With the foregoing in view, the invention resides in the novel subject matter hereinafter described and claimed, description being accomplished by reference to the accompanying drawing.

Fig. 1 is a perspective view of a thread cleaner constructed in accordance with this invention.

Fig. 2 is a horizontal sectional view.

Figs. 3 and 4 are vertical longitudinal sections on the line 3—4 of Fig. 2 looking in the directions indicated by the arrows A and B respectively.

Fig. 5 is a vertical transverse section on line 5—5 of Fig. 2.

The drawing above briefly described illustrates the preferred form of construction and while this construction will be herein specifically explained, it is to be understood that within the scope of the invention as claimed, minor variations may be made.

The numeral 6 denotes a substantially flat

horizontally disposed, U-shaped body whose arms 7 are provided with longitudinal grooves 8 in their inner edges while the arm-connecting portion 9 of said body is provided with a recess 10 which registers with said grooves, the top and bottom of the recess and the corresponding portions of the grooves being in common planes. Then too, the outer sides 11 of the grooves 8 are continuous with the corresponding walls of the recess 10, and for a purpose to appear, these side walls 11 are at acute angles to the groove bottoms.

The arm-connecting portion 9 of the body 6 is provided with an integral upstanding boss 12 having a bore 13 whose lower end is enlarged as at 14. A tubular, key-operated set-screw 15 is threaded in the bore 13 and the operating key for said set screw is shown partially at 16. To guard this screw against tampering with an instrument other than the key 16, the boss 12 is provided with a continuous inwardly projecting flange 17 over said screw. This screw is instrumental in clamping two thread-cleaning blades 18—19 in relatively adjusted position so that the desired space 20 exists between them to receive the thread.

The blade 18 is rearwardly widened and is received in the groove 8 of one of the arms 7, while the blade 19 is rearwardly narrowed and is received in the groove 8 of the other arm 7, the rear portions of both blades being received in the recess 10. The outer edges of the blades are somewhat inclined for snug contact with the groove walls 11 and the corresponding formations of the recess 10, and to compensate for any inaccuracy in manufacture and permit parallel initial setting of the blades 18—19, two set screws 21—22 are threaded through the rear portion of the body 6. Screw 21 abuts the inner end of the blade 18 and screw 22 abuts the outer longitudinal edge of said blade near said rear end. After these screws have been properly set, their heads are preferably filed off so that they cannot be further molested. Then too, these screws are covered by an attaching plate 23 and one of a pair of arms 24 projecting from said plate. The plate 23 abuts the rear end of the body 6, the arms 24 contact with the longitudinal edges of said body, and screws 27 secure said body and arms together.

The inner edges of the blades 18—19 are provided with downwardly converging bevels 28—29 respectively. Shoulders 30 are

formed at the ends of the bevel 28, and an elongated thrust member (preferably a roller) abuts these shoulders at its ends and lies upon both of the bevels 28-29, said thrust member being shown at 31. This member projects upwardly from the blades 18-19 and its ends abut diametrically opposite portions of the side wall of the bore enlargement 14. Thus, member 31 is held against longitudinal shifting and as the shoulders 30 of the blade 18 abut the ends of said member, this blade is held against similar shifting. A washer 32 lies upon the member 31 and is received in the bore enlargement 14 and when this washer is forced tightly down by the set screw 15, not only are the blades 18-19 forced downwardly against the groove and recess bottoms, but the bevels exert a spreading force on said blades, thereby tightly crowding their outer edges against the groove walls 11 and the corresponding formations of the recess 10, and the acute angular formations at the outer edges of the blades co-act with the similar formations of the body 6 in augmenting tight clamping of the blades and insuring that they shall bear solidly upon the lower walls of the grooves.

The beveled portion 29 of the blade 19 is gradually thickened toward its rear end. Hence, by no possibility can this blade be pulled outwardly or forwardly to increase the space 20, as in order to do so, the bevel must raise the member 31 and this cannot be done with the washer 32 and the set screw 15 in operative position. Loosening of the screw 15 permits authorized adjustment with ease however, and in order to prevent total withdrawal of the blade 19 when this screw is loosened, a stop screw 33 is preferably provided, threaded through one of the arms 7 and having its inner end received in a notch 34 in said blade 19.

In order that the roller or the like 31 may lie solidly upon both bevels 28-29 and have its upper side in a truly horizontal plane for contact with the washer 32, the bevel 28 is gradually thickened toward the front end of the blade 18, the longitudinal inclination of this bevel and that of the bevel 29 being the same but in opposite directions.

It will be seen from the foregoing that effective provision has been made for carrying out the objects of the invention and attention is again invited to the fact that while the specific construction shown is preferably followed, variations may be made within the scope of the invention as claimed.

I claim:—

1. A thread cleaner comprising a U-shaped body having longitudinal grooves in the inner edges of its arms and a forwardly opening recess in its arm-connecting portion communicating with said grooves, a rearwardly narrowed blade in the groove of one arm and a forwardly narrowed blade in the groove of

the other arm, the rear portions of the two blades being received in said recess, two set screws threaded through said body and respectively abutting the rear end of said rearwardly widened blade and the outer edge of this blade near said rear end thereof to initially adjust said blade accurately to its proper position, and means for holding the two blades in spaced relation with each other. 70

2. A structure as specified in claim 1; together with an attaching plate abutting the rear end of said body and barring access to one of said screws, and rigid arms on said plate secured to the outer longitudinal edges of said body, one of these arms barring access 80 to the other of said screws. 75

3. A thread cleaner comprising two blades having spaced thread-scraping edges whose spacing is variable by relative longitudinal sliding of said blades, the rear portions of said edges having downwardly converging bevels, a body recessed to receive said blades, and thrust means engaging said bevels for thrusting one side of said blades tightly against the body and for exerting a spreading force on the blades to hold their outer edges tightly against said body. 85 90

4. A thread cleaner comprising two blades having spaced thread-scraping edges whose spacing is variable by relative longitudinal sliding of said blades, the rear portions of said edges having downwardly converging bevels, a body recessed to receive said blades, an elongated member lying against both of said bevels, and a clamping screw threaded in said body to inwardly thrust said elongated member and hold one side of the blades tightly against the body, also exerting a spreading force on the blades to hold their outer edges tightly against said body. 95 100 105

5. A thread cleaner comprising two blades having spaced thread-scraping edges whose spacing is variable by relative longitudinal sliding of said blades, the rear portions of said edges having downwardly converging bevels, a body recessed to receive said blades, an elongated roller lying against both of said bevels, a washer resting upon said roller, and a clamping screw threaded in said body and abutting said washer, said screw being adapted to inwardly thrust said washer and said roller, thereby causing the latter to tightly hold one side of said blades against the body and also causing a spreading force on said blades to tightly hold their outer edges 110 115 120 against the body. 125

6. A structure as specified in claim 3; the beveled portion of one of said blades being gradually thickened toward its rear end to positively prevent it from being pulled forwardly. 125

7. A structure as specified in claim 4; the beveled portion of one of said blades being gradually thickened toward its rear end to positively prevent it from being pulled for- 130

wardly, the other blade and said body being provided with shoulders abutting the ends of said elongated member to positively prevent sliding of said other blade.

- 5 8. A structure as specified in claim 5; the opening of the body in which said screw is received being enlarged at its inner end to receive said washer and having its side wall in contact with the ends of said roller, one of 10 said blades having shoulders at the ends of its bevel abutting the ends of said roller whereby

this blade is positively held against sliding, the other blade having its beveled portion gradually thickened rearwardly to positively hold this blade against forward movement. 15

9. A structure as specified in claim 3; the outer edges of said blades and the contacting surfaces of said body being at acute angles to said one side of said blades.

In testimony whereof I have hereunto affixed my signature.

HARRY J. HUFFORD.
